UNITED STATES PATENT OFFICE

LESTER S. KAUFFMAN, OF RICHMOND HEIGHTS, MISSOURI, ASSIGNOR TO AMERICAN STOVE COMPANY, OF ST. LOUIS, MISSOURI, A CORPORATION OF NEW JERSEY

GAS RANGE CONSTRUCTION

Application filed September 26, 1929. Serial No. 395,269.

The primary object of the invention is the provision of a structure whereby it is possible to conceal both the fuel supply pipe and the mixer face of the burner so that a stove of more pleasing appearance is obtained.

Another further object of the invention is the provision of an air extension sleeve for the inlet of primary air to gas burners used in the ovens and broilers of gas ranges.

Another object of the invention is the provision of air extension sleeves for gas burners of a novel and improved construction which are cheap and simple of manufacture and highly efficient operation and are further so designed as to lend to the appearance of the stove or range upon which they are used.

Other novel features of construction, objects and improved results of the invention will appear from the following description and accompanying drawings.

In the drawings:

Figure 1 is a view in front elevation showing the lay-out of the fuel supply pipes and the burners for the broiler and oven of a gas range, the view further illustrating the application of my improved air extension sleeve to the burners.

Figure 2 is a top plan view of Figure 1.

Figure 3 is an enlarged detail front view of the air extension sleeve.

Figure 4 is a vertical sectional view illustrating the application of the air extension sleeve to the mixer face of the burner.

Figure 5 is a transverse sectional view of the structure appearing in Figure 4.

Figure 6 is a horizontal sectional view of a modified form of air extension sleeve.

Figure 7 is a vertical sectional view of the structure appearing in Figure 6.

Figure 8 is a vertical sectional view of a still further modification of air extension sleeve structure.

Figure 9 is a horizontal sectional view of the structure appearing in Figure 8.

Figure 10 is a vertical sectional view of still another modified form of air extension sleeve structure.

At the present time gas stoves and ranges in which the gas supply pipe is concealed have come into extensive use as they are more

pleasing in appearance by not having an unattractive looking gas supply pipe external of the stove or range.

In the past where the gas supply pipe has been externally arranged the pipe has been carried to the sides of the range oven and broiler and provided with a gas cock or jet for the delivery of gas into the end of the oven and broiler burners. The ends of the burner which receive the gas are provided with a shutter arrangement to control the admission of primary air to accomplish a proper mixing and as a consequence this inlet end of the burners has been termed the mixing face of the burner. In those stoves and ranges having an external gas supply conduit the mixing faces of the burners were always visible and they too detracted from the appearance of the range.

The present invention is on an air extension sleeve and cover for the mixing tubes of burners used in the broiler and oven of gas ranges wherein both the mixing faces of the burners are concealed as is also the gas supply pipe or manifold for the burners.

Figures 1 and 2 illustrate a suggested layout for a gas cooking range wherein the burners as well as the gas supply pipe are concealed and the mixing tubes of the burners have applied thereto my improved air extension sleeve and cover attachment.

In these two figures of the drawings A represents the broiler of the range and B the oven. The broiler burner is designated as 15 and the oven burner as 16. The gas supply for the oven burner is in the form of a pipe or conduit 17 which has one end 18 attached to the cooking top gas supply manifold 19 which is concealed below the top 20 and behind the face plate 21. This pipe 18 extends rearwardly through the cooking top burner chamber and across the back of the range and enters the oven through its rear wall and between its outer end wall 22 and the oven lining wall 23. This pipe can of course run directly to the air extension sleeve C where the range is not thermostatically controlled, but in the drawings a thermostatic control for the range is illustrated and as a consequence the gas supply pipe 17 is in connection with

this thermostat D which controls the distribution of gas through a short extension pipe 24 to the air extension sleeve C, which pipe 24 is also concealed within the lining of the 5 range oven.

The broiler burner 15 is supplied gas by a pipe 25 which is in the lining of the oven and broiler compartments and terminates at one end in the air extension sleeve E while the 10 opposite end of this pipe 25 is connected to the gas supply pipe 19 concealed within the cooking top burner chamber.

Through experimentation I have found that air extension sleeves of varying constructions can be used with success although the same inventive principle is present in all of the different forms of sleeve attachments. Several forms of the air extension sleeves are illustrated in the drawings 15 20 from Figure 3 to Figure 10 inclusive and a detailed description of these air extension sleeves and their structural features follows.

At this time it might be well to state that in respect to all of the forms of the invention 25 the sleeves are provided with a cover plate F which is positioned externally of either the oven or the broiler. This cover is circular in form and provided with a plurality of air inlet openings 27. This cover plate is con- 30 caved or convex in cross section and positioned so that it bulges slightly outwardly from the external faces of the range. As the greater majority of ranges at the present time are provided with an enamel finish this 35 cover plate is likewise provided on its outer face with an enamel finish so that it will blend with the range finish and not detract from the range appearance. This plate is a vast improvement from the standpoint of appearance over the mixing face of the range burners which it replaces.

Referring now to Figures 4 and 5 of the drawings it will be seen that the burner is designated as 15 and its mixing face or bell 45 as 28. This bell at its outer end is provided with the usual shutter 29 for controlling the inlet of primary air to the burner.

The oven or broiler lining wall is designated at 23 while the external wall of the broiler or oven is designated at 22. It will be seen that the mixing bell and its shutter terminate in the space 30 between these two walls and that an air extension sleeve G is provided for use with the burner. This air extension sleeve constitutes an open ended tubular member 31 the inner end 32 of which surrounds the mixing face and bell of the burner while its opposite end is provided with a laterally bent or formed circumferential flange 33 which abuts the outer face of the range wall 22 adjacent the circular opening 34 provided therein for the reception of the sleeve. Incidentally the lining wall 23 is likewise provided with a circular opening 35

for the reception of the inner end 32 of the sleeve.

The gas supply pipe 24 is positioned in the space 30 between the range wall and the oven lining and carries at its lower end an inwardly extending jet 36 which passes through the shutter 29 and a suitable opening 37 in the burner bell for the delivery of gas into the mixing tube of the burner 15. 70

This air extension sleeve is closed at its outer end by the cover plate F heretofore mentioned and in the manufacture of the sleeve this cover is welded to the sleeve flange 33 as at 38 so that the air extension sleeve 75 as an entirety comprises the two parts 31 and 80 the plate F.

This sleeve is supported in place by the gas supply pipe 24 which has an outwardly extending stud 39 terminating in a threaded portion 40 backed by a collar 41. The plate 85 F and the sleeve are clamped against this collar 41 by a suitable draw-up nut 42.

To make the sleeve readily attachable and detachable without the necessity of disturbing the fuel supply pipe the sleeve 31 is provided with a notched or cut-out portion 43 of a size slightly larger than the diameter of the fuel supply pipe 24. This construction makes it possible to slide the sleeve into and out of place as desired and when it is 90 positioned to clamp it in place by the draw-up nut 42.

Referring now to Figures 6 and 7 of the drawings, a slightly different construction is illustrated but here again we have a fuel supply pipe 24 in the space 30 between the outer range wall 22 and the lining wall 23. 100

In this form of the invention the mixing bell 28 of the burner extends further into the space between the walls than was the case 105 in respect to the structure illustrated in Figures 4 and 5 of the drawings, and as a consequence the lower end of the gas supply pipe is provided with an outwardly curved or goose-necked portion 44 so as to carry the gas 110 supply outwardly in front of the burner bell to permit the inward extension of the supply jet or nozzle 36 through the mixing face shutter 29 and the opening 37 of the burner mixing tube. 115

In this form of air extension sleeve construction the sleeve 45 has its one end 46 surrounding the mixing face and bell end of the burner and is provided with a notched or cut-out portion 47 for the passage of the goose 120 necked end 44 of the fuel supply pipe. The opening in the outer wall 22 of the range is flared inwardly as at 48 to provide a circumferential flare which is abutted on its inner face by the circumferentially flared end 49 125 of the sleeve and the two are suitably welded together so that the sleeve is supported in place.

As a consequence the cover plate F is a piece altogether separate from the sleeve and it is 130

held in place by the draw-up nut 42 carried on the threaded portion of the stud 39 which is a part of the goose necked gas supply pipe 44.

5 Due to the fact that the burner mixing bell extends further into the space 30 and the curvature of the gas pipe portion 44 the cover plate F in this structure is slightly more concaved or bulged than is the cover plate in the structure appearing in Figure 4 of the drawings.

10 Figures 8 and 9 of the drawings illustrate still a further modified construction of air extension sleeve and in this construction the air extension sleeve 50 is a separate member 15 from the cover plate F and the two are preferably made in castings.

The gas supply pipe 24 is positioned in the space 30 between the outer range wall 22 20 and the lining wall 23 and is provided with a fitting 51 carrying the gas jet or nozzle 36 extending through the shutter 29 through the opening 37 of the mixing bell 28 into the end of the mixing tube for delivery of gas to 25 the burner.

25 The cover plate is again held in place by the draw-up nut 42 mounted on the threaded portion 40 of the stud 39 provided on the gas supply pipe fitting 50 but in this instance 30 the cover plate is provided with an inset circumferential flange 52 to form an L-shaped seat 53 to receive the edges of the outer wall surrounding the opening which receives the flange 52 of the plate.

35 In this construction the air extension sleeve 50 at its top has cast integrally therewith a supplemental stub sleeve 54 through which the fuel supply pipe 24 passes. This stub sleeve 54 is provided with a thickened portion 55 in which is threadedly mounted a set-screw 56 and by tightening this set-screw tight against the fuel supply pipe 24 the collar is rigidly supported in proper position in respect to the mixer face of the burner 40 tube.

45 In this construction the air extension sleeve is tapered outwardly while its inner end 57 passes through the opening 58 in the lining wall 23.

50 Figure 10 illustrates a still further modified form of the invention and is a construction wherein the air extension sleeve 59 at its inner end 60 abuts the circumferential shoulders 61 of the mixing bell 28 of the burner 55 tube 15 while its outer end is provided with a circumferential flange 62 which at a plurality of points throughout its circumference is bolted as at 63 to the outer range wall 22.

60 In this structure the gas pipe 24 is again positioned in the space 30 between the outer range wall 22 and the lining wall 23 and a goose necked fitting 64 carries the gas from 65 the lower end of the supply pipe 24 into the

mixing bell through the medium of the jet or nozzle 36.

The cover plate F is clamped against the outer face of the outer range wall 22 by the draw-up nut 42 mounted on the threaded portion 40 of the stub shaft 39 cast integrally with the goose necked portion 64 of the gas supply pipe conduit.

70 From the foregoing it will be seen that I have provided numerous constructions of air extension sleeves to take care of the inlet of primary air to the mixing face of a burner tube which is concealed within the oven or broiler or the linings of a gas range.

75 Although the present invention has been described and illustrated as applicable to the oven and broiler burners of a range, the inventive idea could be utilized in respect to the cooking top constructions of ranges, room heaters, etc., without departing from the spirit of the invention.

80 Having thus described my invention what I claim and desire to secure by Letters Patent is:

1. A gas range construction, comprising an oven having concealed therein a burner and a fuel delivery pipe therefor, an air extension conduit for said burner, said conduit comprising a tubular sleeve having an open end communicating with the burner and carrying at its opposite end a ported cover plate externally of the oven, and said plate and sleeve supported in position upon said fuel supply pipe. 90

95 2. A gas range construction, comprising an oven having concealed therein a burner and a fuel delivery pipe therefor, said oven provided with an opening opposite the fuel receiving end of the burner, an air extension conduit comprising a tubular sleeve and a ported cover plate, said sleeve provided with a slot for the reception of said fuel delivery pipe, and said sleeve mounted in said oven opening with one end in communication with the burner and removably supported upon said fuel supply pipe, for the purpose described. 100

105 3. A gas range construction, comprising an oven having a lining therein, a burner in the oven having a mixing tube the outer end of which protrudes into the space between the outer oven wall and the wall lining, a fuel delivery pipe positioned in the space between the oven wall and the oven lining for delivering fuel to the burner mixing tube, an air extension conduit for said burner mixing tube, said conduit comprising a tubular sleeve having one end in communication with the burner mixing tube and its opposite end external of the oven and provided with a rigidly secured ported cover plate, a slot in said tubular sleeve for the reception of the fuel supply pipe, and said sleeve and plate removably supported upon the fuel supply pipe, for the purpose described. 110

115 120 125 130 135

4. A gas range construction, comprising an oven having concealed therein a burner and a fuel delivery pipe therefor, said burner having a mixing tube, said oven wall provided with an opening opposite the end of said burner mixing tube, and an air extension sleeve mounted in said oven wall opening, said extension sleeve having communication at one end with the burner mixing tube 10 and its opposite end in communication with the atmosphere external of the oven wall.
5. A gas range construction, comprising an oven and a lining therefor, a burner and a fuel delivery pipe therefor concealed in the oven, the fuel delivery pipe positioned in the space between the oven lining and the oven wall, said oven wall and oven lining provided with aligned openings, said burner provided with a mixing tube having an end 15 extending through the oven lining opening into the space between the lining and the oven wall, and a primary air inlet extension conduit for said burner mixing tube removably supported in said aligned openings.
6. A gas range construction, comprising an oven having concealed therein a burner and a fuel delivery pipe therefor, said burner provided with a mixing tube and the oven wall with an opening opposite the end of said mixing tube, the edges of the oven wall surrounding said opening being flared inwardly, and a primary air inlet extension conduit for said burner mixing tube having a flared end abutting and supported by the flared 20 edge of the oven wall opening, for the purpose described.
7. A gas range construction, comprising an oven having concealed therein a burner and a fuel delivery pipe therefor, said burner provided with a mixing tube and the oven wall with an opening the edges of which are flared inwardly, a primary air inlet extension conduit for said burner mixing tube having an opening for the passage of the fuel supply 25 pipe and a flared edge abutting and supported upon the flared edge of the oven opening, and a ported cover plate for the oven wall opening removably supported upon the fuel supply pipe, for the purpose described.
8. A gas range construction, comprising an oven having concealed therein a burner and a fuel delivery pipe therefor, said burner provided with a mixing tube and the oven wall with an opening opposite the end of said mixing tube, a primary air inlet extension conduit for said burner mixing tube having its outer end in communication with said oven 30 wall opening, said air extension conduit provided with a sleeve for the reception of the fuel supply pipe, a set-screw carried by said conduit sleeve and adapted to be tightened against the fuel supply pipe for supporting the conduit in position, and a ported cover plate positioned in said oven wall opening
9. A gas range construction, comprising an oven having concealed therein a burner and a fuel delivery pipe therefor, said burner provided with a mixing tube and the oven wall with an opening opposite the end of said mixing tube, a primary air inlet extension conduit for said burner mixing tube, the outer end of said conduit provided with a peripheral flange by which the conduit is secured to the edges of the oven wall surrounding said oven wall opening, and a ported cover plate for said oven wall opening removably supported upon the fuel supply pipe. 70
10. A gas range construction, comprising an oven having concealed therein a burner and a fuel delivery pipe therefor, said burner provided with a mixing tube and the oven wall with an opening opposite the end of said mixing tube, a primary air inlet extension conduit for said burner mixing tube, said conduit comprising a tubular sleeve the outer end of which is provided with a circumferential flange adapted to abut the edges of the oven wall surrounding the opening therein, a ported plate rigidly secured to the outer end of the conduit, a slotted opening for the reception of the fuel supply pipe, the fuel supply pipe provided with an outwardly extending threaded stud adapted to pass through the cover plate, and a draw-up nut carried by said fuel pipe stud, whereby the conduit is removably supported in the oven wall opening, for the purpose described. 75
11. A gas range construction comprising an oven having therein a burner and a fuel delivery pipe therefor, an air extension conduit for said burner, said conduit comprising a tubular sleeve having an open end communicating with the burner and carrying at its opposite end a ported cover plate externally of the oven, said fuel supply pipe provided with an extension, and said plate and sleeve supported upon said fuel pipe extension. 80
12. A gas range construction, comprising an oven having concealed therein a burner and a fuel delivery pipe therefor, said oven provided with an opening opposite the fuel receiving end of the burner, an air extension conduit comprising a tubular sleeve and a ported cover plate, said sleeve provided with a passageway for the reception of said fuel delivery pipe, and said sleeve mounted in said oven opening with one end in communication with the burner and removably supported upon said fuel supply pipe, for the purpose described. 85
13. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 90
14. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 95
15. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 100
16. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 105
17. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 110
18. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 115
19. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 120
20. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 125
21. A gas range construction, comprising an oven having a lining therein, a burner in the oven having a mixing tube the upper end of which protrudes into the space between the outer oven wall and the wall lining, a fuel delivery pipe positioned in the space between the outer oven wall and the wall lining, and a ported cover plate positioned in the oven wall opening removably supported upon the fuel supply pipe. 130

the oven wall and the oven lining for delivering fuel to the burner mixing tube, an air extension conduit for said burner mixing tube having one end in communication with the 5 burner mixing tube and its opposite end external of the oven and carrying a ported cover plate, a passageway in said conduit for the reception of the fuel supply pipe, and said conduit and plate supported upon the 10 fuel supply pipe, for the purpose described.

14. A gas range construction, comprising an oven and a lining therefor, a burner and a fuel delivery pipe therefor concealed in the oven, the fuel delivery pipe positioned 15 in the space between the oven lining and the oven wall, said oven wall and oven lining provided with openings, said burner provided with a mixing tube having an end extending through the oven lining opening into 20 the space between the lining and the oven wall, and a primary air inlet extension conduit for said burner mixing tube positioned in said oven wall and lining openings.

15. A gas range construction, comprising 25 an oven having concealed therein a burner and a fuel delivery pipe therefor, said burner provided with a mixing tube and an oven wall with an opening opposite the end of said mixing tube, a primary air inlet extension conduit for said burner mixing tube having a flared end abutting and supported by the oven wall, and a ported cover plate for the open outer end of said primary air inlet extension, for the purpose described.

35 16. A gas range construction, comprising an oven having concealed therein a burner and a fuel delivery pipe therefor, said burner provided with a mixing tube and an oven wall with an opening the edges of which are 40 flared inwardly, a primary air inlet extension conduit for said burner mixing tube having an opening for the passage of the fuel supply pipe and a flared edge abutting and supported upon the flared edge of the oven opening, and a ported cover plate for the oven 45 wall opening, for the purpose described.

17. A gas range construction, comprising 50 an oven and a lining therefor, a burner and a fuel delivery pipe therefor concealed in the oven, the fuel delivery pipe positioned in the space between the oven lining and the oven wall, said burner provided with a mixing tube having a bell shaped end, said bell shaped portion of said mixing tube being 55 positioned in the space between the oven wall and the oven lining, an opening in the oven wall opposite the end of said mixing tube, a primary air inlet extension conduit having one end in communication with the oven wall 60 opening and its other end in communication with the end of the burner mixing tube, said fuel delivery pipe provided with a goose-neck passing through said primary air inlet extension conduit and extending outwardly 65 through the oven wall opening, said goose-

neck provided with an extension, and a ported cover plate for the end of said primary air inlet conduit supported upon said gas delivery pipe goose-neck extension, for the purpose described.

70 18. A gas range construction, comprising an oven having concealed therein a burner and a fuel delivery pipe therefor, said burner provided with a mixing tube and the oven wall with an opening adjacent the end 75 of said mixing tube, a primary air inlet extension conduit for said burner mixing tube having its outer end in communication with said oven wall opening, said air extension conduit provided with a sleeve for the reception of the fuel supply pipe, a clamp carried by said conduit sleeve and adapted to tighten upon the fuel supply pipe for supporting the conduit in position, and a ported cover plate positioned in said oven wall opening, for the purpose described.

80 19. A gas range construction, comprising an oven having concealed therein a burner and a fuel delivery pipe therefor, said burner provided with a mixing tube and an oven 90 wall with an opening adjacent the end thereof, a primary air inlet extension conduit for said burner mixing tube, the outer end of said conduit provided with a peripheral 95 flange by which the conduit is secured to the oven adjacent the wall opening therein, and a ported cover plate for said oven wall opening, for the purpose described.

100 In testimony whereof I hereunto affix my signature.

LESTER S. KAUFFMAN.
